UNITED STATES PATENT OFFICE.

CLAYTON A. BALLOU, OF PROVIDENCE, RHODE ISLAND.

ELECTRIC TIME-SWITCH.

No. 830,041.

Specification of Letters Patent.

Patented Sept. 4, 1906.

Application filed June 30, 1905. Serial No. 267,734.

To all whom it may concern:

Be it known that I, CLAYTON A. BALLOU, a citizen of the United States of America, and a resident of Providence, in the county of 5 Providence and State of Rhode Island, have invented certain new and useful Improvements in Automatic Electric Time-Switches, of which the following is a specification.

This invention relates to "cut-outs," so-called, adapted to be automatically actuated in an intermittent manner at certain prearranged times or intervals.

The present invention embodies the combination with a suitable quick-acting positively-driven mechanical device, of a contact-switch taking its movements from said mechanism, and an intermittently-revolv¹⁵ing cut-out device interposed between said switch and mechanism, the latter also controlling the movements of said cut-out device.

In the accompanying drawings, Figure 1 is a front side elevation, in partial section, representing the present invention, the electric circuit being closed. Fig. 2 is a similar view, the circuit being broken or open. Fig. 3 is a partial side view showing the relation of the parts when the cut-out device itself is brought into action to temporarily keep the 25 circuit open. Fig. 4 is a partial plan view of the cut-out, taken on line xx of Fig. 3. Fig. 5 is a partial end elevation, showing a pair of mercury-cups, &c., corresponding with the position shown in Fig. 1; and Fig. 6, Sheet 30 2, is a front elevation, in reduced scale, showing my improved automatic electric time-switch combined with suitable time mechanism, the position of the parts of the device being substantially as represented in Fig. 1.

In carrying out the invention or improvement I employ means for intermittently opening and closing the electric circuit. As drawn, a star-wheel a and front and rear cam-wheels or members a' a'' are suitably positioned and secured together and mounted to revolve in unison on the fixed supporting pin or stud e , extending horizontally from the face of the vertical frame b . d' d'' indicate two swinging front and rear arms or levers 40 pivoted at e' e'' , respectively, to said frame, each provided on its lower side with an extension or member in frictional engagement with the periphery of its respective cam. The front lever d' is weighted and bears against a 45 lateral extension d'' , formed on the short arm of lever d'' . Intermittent rotary movement

is or may be imparted to said star and cam wheels by means, say, of a continuously-revolv⁶⁰ing clock-driven disk or dial f , secured to the clock-spindle f' and provided with lateral pins f' f'' . (See also Fig. 6.) Said pins in moving through the circular path successively engage the teeth of the star-wheel and rotate it a short angular distance or one tooth, thereby at the same time causing the said 65 cams to correspondingly swing the levers in vertical planes. I make no specific claim, however, to said levers or to means for actuating them. The dial f may make one revolution each day of twenty-four hours, thereby, 70 in coöperation with said wheels, &c., together with other means about to be described, opening and closing the electric circuit once per day, the length of the intervals being determined by the relative position or angular distance apart of the pins.

If mercury contact means be employed, the cups or mercury-containers, as h h' , of the switch are or may be constructed and connected with the main conducting-wire of an 80 electric circuit in any well-known or suitable manner. As drawn, Fig. 1, the conducting-shank h^2 of the cup passes through insulation m of a base or table m' and is secured in position by a nut n . The main conductor u is 85 severed, one end being secured to the shank h^2 by a binding member u' , the other end (not shown) of the wire being secured in like manner to the fellow cup h' . The outer or free end of said lever d^2 has secured thereto a 90 non-conducting arm or member g , in which is movably mounted a U-shaped contact or conductor element i , its two end portions, as drawn, being bent and passing downwardly freely through the covers of the respective 95 cups and when in service into the mercury. (See Fig. 1.)

Interposed between the cups and said star-wheel is mounted a revoluble wheel or cut-out device p , having a series of peripherally-spaced pins p' extending horizontally from the face thereof. Said pins are arranged with respect to and are adapted to be successively engaged by the teeth of wheel a , the latter causing the member p to revolve in an 100 intermittent or step-by-step manner. As drawn, the wheel p is divided by the pins p' into fourteen equidistant spaces s' , one of them being bridged by a short bar s'' . When the time-switch mechanism is in normal operation, each daily revolution of the clock-driven disk f will, through the medium of the 105

engagement of the teeth of wheel a with said pins p' , move the cut-out wheel p an angular distance corresponding, say, to two spaces, being one-seventh of a complete revolution.

- 5 The corresponding movements of the levers d', d^2 are normally effected and controlled by the cams a', a^2 and said members f and a , the result being to automatically close and open the electric circuit once per day, or, in other 10 words, the lever d^2 swings the contact member i into and out of the mercury contained in the cups during said period. Thus far during the operation the wheel p has not been brought into action except to move idly 15 on its axis. Now in case it is desired to prevent the circuit from closing at any time during the regular or normal working of the apparatus the lever d^2 is provided with a depending short arm or extension d^4 , (adapted 20 to freely enter the spaces s' as the latter are successively brought into position or in alignment thereunder by the rotation of the wheel p .) arranged to rest upon and be supported by the said bridge or bar s^2 , the latter having 25 been already or previously positioned, so as to be brought by the wheel's action directly under said extension d^4 upon the arrival of a previously-selected hour or day, thus for the time being keeping the circuit broken and 30 preventing the member i from entering the mercury. (See corresponding position of the parts as represented in Fig. 3.) At the same time, however, the normal movements of the several elements of the actuating 35 mechanism are in no wise interrupted or affected, except the temporarily-arrested full action of the lever d^2 , as before stated.

In order to prevent the cut-out wheel p from turning rearwardly, I provide a thin 40 swinging pawl t , its forward end being adapted to freely enter the space s' between each pair of pins. The pawl is pivoted at t' to the frame b and is weighted at t^2 to insure its proper working. (See Fig. 4.)

45 While I have represented my invention as combined with actuating mechanism adapted to a switch in which the electric circuit is closed by "mercury contact," so called, I do not desire to specifically limit the combination to such type of switch.

The present improvement is employed only as a circuit-breaker. The periodical intermittent movements of the time-switch mechanism proper and the corresponding periodical opening and closing of the electric circuit are normally unaffected by the presence of the revolute circuit-breaker device, except when the wheel p in its advancing movement carries the previously-adjusted bridge

s^2 in position to arrest the lever d^2 in its downward movement, and thus temporarily prevent the closing of the circuit, substantially as hereinbefore stated.

60 I claim as my invention and desire to secure by United States Letters Patent— 65

1. In an automatic electric time-switch provided with suitable time mechanism, the combination of a revolute disk or member f connected with and actuated by said time mechanism, a self-dropping swinging arm or lever having a current-conducting member mounted in its free end, intermittently-revolute mechanism actuated by said disk member for imparting vibratory movements to said lever, a revolute wheel having its movements actuated by said lever-operating mechanism, a pair of poles or terminals located in an electric circuit, and means movable with said wheel for engaging the lever at predetermined intervals to prevent the current-conducting member thereof from contacting with said poles and closing the circuit.

70 2. In a device of the character described, the combination in an electric circuit with a time mechanism, a revolute star-wheel, a swinging contact-carrying lever, and means operatively connected with the time mechanism for imparting intermittent movements to said wheel and lever, of a revolute wheel p actuated in a step-by-step manner by 75 means of said star-wheel, and having the latter provided with a bridge or member adapted when in use to automatically and temporarily engage said lever at predetermined intervals to arrest its movement and prevent it 80 from closing said circuit.

3. In a device of the character described, a revolute wheel p provided with peripherally-spaced pins, a suitably-disposed bridge or tie uniting some of said pins, and a swinging 85 check-pawl for holding the wheel in position.

4. The combination in a time-switch with a revolute star-wheel and a swinging contact-carrying lever d^2 provided with an extension d^4 on its under side, of the circuit-breaker wheel p , adapted to be actuated by 90 said star-wheel, having peripherally-spaced pins and spaces and a bridge s^2 connecting a pair of pins, adapted when in use to be engaged by said extension d^4 for temporarily 95 preventing the full action of said lever, for the purpose hereinbefore set forth.

Signed at Providence, Rhode Island, this 100 28th day of June, 1905.

CLAYTON A. BALLOU.
